Application August 19, 1950, Serial No. 180,357

3 Claims. (Cl. 8—150.5)

1

This invention relates to methods of and machines for treating hides with liquid, and more particularly to a method of and a machine for intimately contacting a hide with a fluid by working or vibrating successive narrow portions of the hide while those portions are in contact with the fluid.

With the view of avoiding excess verbiage the term "hide" as used herein is intended to refer to either a "hide" or a "skin" and the term "fluid" is used to indicate either liquid or vapor.

Although not limited thereto, the invention is described with particular reference to the "wetting back" of heavy hides. This operation, as heretofore carried out, generally consumes considerable time for in such cases fluids do not penetrate the work as quickly as would be desirable. The "wetting back" is an operation designed to condition the work for subsequent operations. Other operations such as liming, bating and also tanning have consumed considerable time because of the length of the soaking period found necessary as such soaking has heretofore been practiced. Whereas it sometimes takes hours for a treating liquid adequately to penetrate a hide for a given purpose, such a hide may, in using the present invention, be thoroughly permeated by the treating liquid in a few minutes—this comparatively short interval of time varying to some degree with the thickness of the work, the type of tannage or other factors such as the strength of the treating fluid, the temperature and the pH value of the fluid.

An object of the present invention is to provide an improved method for the treatment of hides with liquid which method gives rise to a more rapid penetration of the liquid into the hides than heretofore experienced. Another object is to provide an improved machine which will serve to work or vibrate hide material in successive localized strips or portions and make it more receptive to simultaneous penetration by treating fluids.

A feature of the present invention is the feeding of a work piece along a predetermined path leading through a narrow work treatment zone in a fluid bath and the individual vibrating of successive cross-sectional portions of the work while in contact with the fluid in that zone and in directions substantially normal (i. e. perpendicular) to the path of feed. Another feature resides in the combination of elements in which a member is slotted to receive the full cross section of a work piece to be treated and which member is mounted for reciprocatory movements

5 to impart momentary and limited distortion to individual and successive narrow strips or portions of the work as the latter is contacted by the treating fluid. Preferably and as illustrated, the member for imparting such movements or vibration comprises a pair of cooperating blades with opposed edges for contacting opposite sides of successively fed narrow cross-sectional strips or portions of a hide, these blades operating in a zone of liquid and in vibratory relation with work guides contiguous to each side of the pair of blades.

10 The invention will now be more particularly described by reference to the accompanying drawings and thereafter pointed out in the claims.

In the drawings,

15 Fig. 1 is a perspective view of the left side and rear of a machine constituting one embodiment of an apparatus suitable for carrying out the present invention;

20 Fig. 2 is an elevational view of the right-hand side of a major portion of the machine shown in Fig. 1, drawn to a larger scale and with one section broken away for ease of illustration;

25 Fig. 3 is a sectional view along the line III—III of Fig. 2;

Fig. 4 is a sectional view along the line IV—IV of Fig. 3 and drawn to a still larger scale;

30 Fig. 5 is a sectional view taken along the line V—V of Fig. 4;

35 Fig. 6 is a sectional view of some of the main operative parts as shown in Fig. 5 but with those parts in different relative positions as assumed during a different portion of the operation cycle; and

Fig. 7 is a detail view partially in section illustrating the type of construction employed in mounting the blades in the machine.

The machine is provided with a base plate 10 and two side plates 12 and 14 joined by a top plate 16, these plates making a box-like structure with open sides at front and rear through which a horizontal liquid container or tank 18 is mounted. The container 18 is slidable with relation to the sides 12 and 14. Rigidity is given to the container 18 by transverse members 20 and 22 having depending vertical flanges 21 and 23 (Fig. 5). A heavy transverse member 24 is mounted horizontally between the members 20 and 22 and its ends abut and are in slidable relation to the plates 12 and 14. The member 24 supports the container 18 and the main operative parts of the machine and steadies the latter parts despite the severe stresses employed as will fur-

ther appear. The depending flanges 21 and 23 are attached to the member 24 by bolts 26. A feed roll assembly 30 (Fig. 5) is employed on each side, above and parallel with the heavy member 24 and within the tank 18. These feed roll assemblies 30 are of conventional construction and are composed of resiliently or yieldingly mounted upper rolls 32 and fixed lower rolls 34, the latter having roughened cylindrical surfaces. The feed roll assemblies 30 are firmly located in position by bolts 40 which extend through the transverse members 20 and 22.

At the front of the machine the container 18 is provided with a plate member 41 which is inclined downwardly to a point adjacent to the bite between the rolls of the front feed roll assembly 30 (Figs. 2 and 5). At the rear of the machine the container 18 is provided with an upwardly and rearwardly inclined plate 44 which leads from the bottom portion of the rear feed roll assembly 30.

A shaft 50 is journaled in the upper rear portions of the side plates 12 and 14 and a flywheel 52 is attached thereto and adapted to rotate therewith. The hub of the flywheel 52 is in the form of a pulley 53 to be driven by a belt 54 leading from a source of power supply (not shown).

A bracket 56 is attached by bolts 58 to each of the plates 12 and 14, as viewed in Fig. 3. Each of the brackets 56 has a pair of depending flanges 58 and 59 which are perforated by a row of holes 60 (Fig. 2) and these holes extend through the corresponding side plate 12 or 14. Each set of aligned holes is adapted to receive a pin 64 arranged to be inserted through a side plate and having a knurled head 66. Each of these two pins 64 is adapted to serve as a pivot as will further appear and the series of sets of holes serve for changing the locations of the pins 64 as a means of adjustment of the range of relative motion for main operative parts of the machine. Each end of the shaft 50 is provided with an eccentric 68, which is adapted to drive an arm 70 pivoted at 72 to the rear end of a substantially horizontal lever 74. This lever 74 has holes corresponding with the holes 60 formed in the flanges 58 and 59. Each of the levers 74 extends beyond its bracket 56 toward the front of the machine and is pivoted at 80 to the upper end of a substantially vertical bar 82 which in turn is pivoted by means of a short pin 84 to a vertically slidable block 86. Each block 86 is in close fitting slidable relation with the walls 88 and 89 of a large vertical slot cut in each of the walls 12 or 14. Each rod 82 extends some distance below its pivot pin 84 and is provided with a reduced end portion 90 (Fig. 7) to which is attached a member for distorting successive narrow portions of the work. This member comprises blades 92 and 94 and the ends of the two blades 92 and 94 are spaced by elements or washers 96 interposed. The lower end of each rod 82 is threaded at 98 to receive a nut 100 which holds the blades 92 and 94 in proper assembled relation.

The blades 92 and 94 extend transversely of the machine and present a narrow slot 96 (Fig. 7) between them. The lower edge of the blade 92 is smooth and rounded in contour and the same is true of the upper edge of the blade 94, this construction being plainly discernible in Figs. 5 and 6 of the drawings. The machine is so assembled that the slot 96 between the blades is substantially or nearly in alinement with the bites between the rolls in the feed roll assemblies 30.

Located within the container 18 and contiguous

to each side of the blade 94 is located a rigid block member 102 having an L-shaped cross section. The distance between the two blocks 102 determines the width of a narrow work treatment zone extending the full width of the widest work piece to be treated. The top side of each end of each block member 102 is recessed to receive the head 104 of a bolt 106 which passes down through a horizontal slot 108 cut in the member 102, through the bottom of the container 18, and through the heavy member 24. A nut 110 is placed on the bottom end of the bolt 106 to hold the parts in their proper adjusted positions. Each end of each block 102 is threaded at 114 (Fig. 5) to receive a bolt 116 which is adapted to retain one end of a horizontal member 118 in proper relation to the block 102. A washer 120 is interposed beneath each end of each member 118 to serve as a spacer and these spacers determine the width of slot or clearance between the top surface of each block 102 and its corresponding member 118. It will be understood that the width or height of this slot at least equals the thickness of any work piece to be treated and that its length is more than sufficient to receive the full width of such work piece.

The heavy member 24 is bored at 122 and 124 (Fig. 3) to receive the reduced upper ends of threaded shafts 126 and 128. Each of these shafts is provided with a thrust bearing 130 which rests within a recess in the base plate 10 and has a threaded sleeve or collar to which a gear is secured. The shafts 126 and 128 extend through the base plate 10 and are not rotative with relation thereto. Worm and gear arrangements 132 are provided at the lower end of each of the vertical rods 126 and 128 and the construction is such that they may be operated by an interconnecting horizontal shaft 134 and a manually operable handle 136. The shaft 134, handle 136 and the worm gears are supported by brackets 138 which are attached to the sides of the machine by bolts 139. Rotation of the handle 136 and of the collars within the thrust bearings 130 results in the raising or lowering of the container 18 with respect to the blades 92 and 94.

A motor and gear reduction arrangement 140 (Fig. 1) is mounted adjacent to the base of the machine and is arranged to drive the lower rolls 50 of the two feed roll assemblies 30 by means of a chain 142 connected to the shaft of the lower roll of one of the feed roll assemblies 30 through a sprocket 144. The lower roll in the front feed roll assembly is operated by a suitable chain 146 and sprockets 148 and 150 interconnecting the two feed roll assemblies.

In operation of the device a hide 152 (Fig. 5) is spread out upon the plate 41 at the front of the machine and introduced into the bite of the front feed roll assembly 30 which bite is beneath the surface of the liquid placed in the container 18. Assuming that the motor drive assembly 140 is in operation and that the flywheel shaft 50 is being suitably driven by the belt 54, the blades 92 and 94 and hence the work will be vibrated in a direction substantially normal to the path of the work as the hide 152 passes from one feed roll assembly to the other feed roll assembly through the slots formed between the members 118 and the blocks 102. The vibration of the blades 92 and 94 causes successive narrow strips of the work to be distorted as depicted in Fig. 6 but it will be understood that the form or degree of the work displacement or distortion by the blades may be varied considerably as the blocks

102 as well as the members 118 may be raised or lowered with respect to the field of action of the slot between the blades 92 and 94 as those blades vibrate.

The machine illustrated is suitable for the treatment of heavy leathers and the comparative rigidity of such leathers assures proper feeding of the work along the predetermined path leading to and from the vibratory slotted member or pair of blades. It will be understood that when treating thinner or more flexible work, guiding means or plates (not shown) should be supplemented for leading the work as it is fed by the feed roll assemblies 39 to and from the top surfaces of the blocks 102.

Successive narrow cross sectional portions of each work piece fed through the machine are worked and distorted in such a way that the pores of the work are opened and the work is rendered susceptible of rapid penetration by the fluid placed in the container 18. A suitable frequency for one type of sole leather was found to be about 2400 vibrations per minute but the frequency as well as the amplitude of the vibrations is subject to wide variation.

Having thus described my invention, what I claim as new and desire to secure by Letters Patent of the United States is:

1. A machine for treating hides with liquid comprising a slotted member, a slotted guide contiguous to each side of the slotted member, the slots of said member and guides being in contiguous relation for the passage of a work piece therethrough, means for effecting relative vibration between the member and the guides in directions substantially normal to the path of said work piece, and a liquid container enclosing the slotted portions of the said member and guides.

2. A machine for treating hides with liquid comprising a stationary container for fluid, feed rolls for passing a work piece in spread out condition through said fluid and in a predetermined

path, a pair of cooperating blades with opposed edges presenting a slot between the said edges to encompass said path, a stationary work guide member contiguous to each side of said pair of blades, said guide members having slots for closely confining said work to said path, and power means for vibrating the said pair of blades in a direction substantially normal to said path.

3. A method of treating hides which comprises feeding a spread-out work piece along a predetermined path leading through and transverse to a narrow work treatment zone in a bath of liquid and simultaneously with the feeding individually distorting each of successive narrow cross-sectional portions of said work piece as it is fed through said zone by subjecting said portions to reciprocatory movement in directions normal to the said predetermined path with a high frequency and amplitude adequate to increase penetration of the liquid into the work piece while restraining against reciprocatory movement portions of said work piece adjoining said narrow cross-sectional portions.

MIETH MAESER.
